UNITED STATES PATENT OFFICE.

EDWIN M. CAMPFIELD, OF RICHMOND, INDIANA.

SECTIONAL CONDUIT.

1,093,766.

Specification of Letters Patent. Patented Apr. 21, 1914.

Application filed October 15, 1913. Serial No. 795,296.

To all whom it may concern:

Be it known that I, EDWIN M. CAMPFIELD, a citizen of the United States, residing at Richmond, in the county of Wayne 5 and State of Indiana, have invented a new and useful Sectional Conduit, of which the following is a specification.

This invention relates to sectional conduits and other like structures such as tunnels, sewers, etc., one of the objects of the invention being to provide a structure of this character made up of courses of transversely arched blocks so shaped as to be built up readily and to permit the lowering 10 of the keystone blocks into proper position, there being an arrangement of side, top and bottom keys of peculiar contours and which coöperate with the remaining blocks of the structure to offer the maximum resistance 15 to the downward pressure exerted by the weight above the conduit and the corresponding pressure exerted by the contents 20 of the conduit.

A further object is to provide blocks 25 which can be formed readily, can be easily set up in the construction of the conduit or the like, and which are designed to lap both at their sides and ends, thus to produce a tight and durable structure.

With the foregoing and other objects in view which will appear as the description 30 proceeds, the invention resides in the combination and arrangement of parts and in the details of construction hereinafter described and claimed, it being understood 35 that changes in the precise embodiment of the invention herein disclosed, can be made within the scope of what is claimed, without departing from the spirit of the invention.

In the accompanying drawings, certain forms of my invention have been shown.

In said drawings:—Figure 1 is a vertical transverse section through a conduit embodying the present improvements. Fig. 2 is a central longitudinal section through one of the blocks of the conduit. Fig. 3 is a view similar to Fig. 1 but showing another form. Fig. 4 is an end elevation of a modified form of block.

Referring to the figures by characters of reference 1 designates a base block which, in the form shown in Figs. 1 and 2, has parallel steps 2 and 3 at each side, the said sides converging upwardly and the entire block being arched or curved transversely.

Between the steps 2 is a transverse partition 4 and another transverse partition is arranged between the steps 3, as shown at 5, these partitions 4 and 5 being connected at 60 their centers by a central longitudinal partition 6 so that the interior of the block 1 is thus divided into parallel cells extending throughout the length thereof. As shown in Fig. 2, one end of the block has an outwardly projecting tongue 7 while a corresponding recess 8 is formed in its other end. Thus when the base blocks 1 are arranged end to end to form a course, the tongue 7 of each block will extend into the 70 recess 8 of the next adjoining block, thereby producing an end lap.

Oppositely disposed similar side blocks 9 are employed, each of these blocks being curved or arched from side to side and being provided, at each side, with steps 10 and 11. These stepped sides of the blocks 9 diverge outwardly and formed between the steps 10 is a transverse partition 12 while another corresponding partition 13 is 80 formed between the steps 11. These partitions are preferably parallel with the inner and outer faces of the blocks and any suitable reinforcing means such as curved and straight webs 14 and 15 can be interposed between the partitions and the inner and outer walls of the blocks so as thus to divide the blocks into longitudinal cells extending throughout the lengths thereof. It will be seen that the steps on the side key 90 blocks 9 are disposed oppositely to the steps on the base key blocks 1. In other words, the base block 1 is stepped inwardly while the side blocks 9 are stepped outwardly. This will be apparent by referring to Fig. 1. 95 The side blocks 9 are adapted to lock at their ends in the same manner as do the blocks 1, they being provided with end tongues and recesses corresponding with those shown in Fig. 2.

Interposed between each base block 1 and the corresponding side blocks 9 are lower intermediate blocks 16 arranged in any desired number of courses. In the structure shown in Fig. 1, three courses of these lower intermediate blocks are provided between the base blocks and each side block 9. Each of these blocks 16 is curved or arched transversely and has its lowermost side stepped outwardly while its uppermost side is stepped 105 inwardly. The steps 17 and 18 formed at the lower side of the lowermost blocks 16 are 110

adapted to bear downwardly upon the steps 3 and 2 of the blocks 4. The steps 19 and 20 at the upper sides of the lowermost blocks 16 are designed to receive the downward thrust 5 exerted by the steps 17 and 18 and the next adjoining blocks 16. This arrangement is continued through the several courses of the lower side blocks, the steps 19 and 20 of the uppermost blocks 16 being engaged by the 10 lower steps 10 and 11 of the side blocks 9.

Erected on the side blocks 9 are courses of upper side blocks 21 of the same construction as the blocks 16 but arranged oppositely thereto, the upper sides of these blocks being 15 stepped outwardly while the lower sides are stepped inwardly. The uppermost courses of blocks 20 are held apart by upper key blocks 21 of the same construction as the blocks 16 but disposed oppositely thereto. 20 All of the blocks 16 and 20 are provided with transverse partitions 22 connected at intermediate points by longitudinal webs 23 so that each block is thus provided with cells 25 extending longitudinally throughout the length thereof. Furthermore the blocks 16, 20 and 21 have their ends disposed in lapped relation in the same manner as the blocks 1.

It is to be understood that the various courses of blocks used in building the conduit are to be connected by means of a suitable cement and that the various blocks can 30 be made of any desired material such as concrete, clay, or other plastic material. The conduit is to rest upon a bed of dirt or other material and after the courses made up of blocks 1 and 16 have been assembled, the side blocks 9 are placed in position. The upper courses made up of the blocks 20 are then set up after which the course made up 40 of the upper key blocks 21 is lowered into position. After the various courses have been assembled and cemented together, any forms necessary in the setting up of the conduit can be removed and the conduit can 45 be covered as ordinarily. It has been found that by arranging the steps on the various blocks as set forth, the downward pressure exerted by the weight above the conduit will be distributed substantially in the direction indicated by the arrows in Fig. 1, the 50 pressures being such that the steps at the lower sides of the blocks 20 will bear downwardly and inwardly upon the next adjoining blocks thereunder while the steps upon 55 the lower sides of the blocks 9 and the lower sides of the blocks 16 will bear downwardly and outwardly upon the next adjoining blocks. Thus collapsing of the conduit under excessive weights is avoided and a 60 strong durable structure provided. Furthermore it will be noted that all of the blocks entering into the construction of the conduit are so shaped as to be easily manufactured and readily placed in position.

65 While each block used in the construc-

tion of the conduit may be formed with two steps at each side, it is to be understood that each block may utilize a single step, as shown, for example, in Fig. 3. Furthermore, and as shown in said figure, the number of courses employed can be reduced and the arrangement of the cells within the blocks may be modified. However, the relative positioning of the stepped faces is the same in the modified structure as that disclosed in Fig. 1. It is also to be understood that instead of utilizing the forms of blocks illustrated in Figs. 1 and 3, the conduit can be made up of courses, the intermediate ones of which consist of blocks such as illustrated, for example, in Fig. 4. This type of block is particularly designed for use where the conduit is to be subjected to excessive pressures, the block being closed at its ends, as shown at 24 and being provided with 70 75 80 85 90 95 100 105 110 115 120 125 130

obviously various other changes may be made in the construction of the blocks, it merely being necessary to step the blocks so that they will fit together in the manner disclosed in Figs. 1 and 3, the lower sides of the upper courses of blocks bearing downwardly and inwardly upon the steps of the upper sides of the next adjoining blocks while the lower sides of the lower courses of blocks bear downwardly and outwardly upon the upper sides of the adjoining blocks. In this manner the lines of force exerted by the weight above the conduit are so distributed as to prevent crushing of the conduit.

Furthermore instead of making the conduit circular as shown in Figs. 1 and 3, it can be made oval, elliptical, or of other curved cross sectional contour, it being necessary of course to provide special shaped blocks for the different courses in order to produce a conduit of the desired contour.

Furthermore while the structure has been described as a conduit, it is to be understood that tunnels, sewers, and other like structures can be built in the same manner hereinbefore described.

What is claimed is:—

1. A conduit or the like made up of superposed courses of blocks, the blocks of the bottom course having their sides stepped inwardly or upwardly, the blocks of the top course having their sides stepped inwardly or downwardly, the blocks of the side courses having their sides stepped outwardly, the blocks of the courses between the bottom course and the side courses having their lower sides stepped outwardly and their upper sides stepped inwardly and the blocks between the side courses and the top courses having their lower sides stepped inwardly and their upper sides stepped outwardly.

2. A conduit or the like made up of superposed courses of blocks, the blocks of the

- bottom course having their sides stepped inwardly or upwardly, the blocks of the top course having their sides stepped inwardly or downwardly, the blocks of the side courses having their sides stepped outwardly, the blocks of the courses between the bottom course and the side courses having their lower sides stepped outwardly and their upper sides stepped inwardly and the blocks between the side courses and the top courses having their lower sides stepped inwardly and their upper sides stepped outwardly, the blocks of all the courses having lapping ends.
15. 3. A conduit or the like made up of superposed courses of blocks, the blocks of the bottom course having their sides stepped inwardly or upwardly, the blocks of the top course having their sides stepped inwardly or downwardly, the blocks of the side courses having their sides stepped outwardly, the blocks of the courses between the bottom course and the side courses having their lower sides stepped outwardly and their upper sides stepped inwardly and the blocks between the side courses and the top courses having their lower sides stepped inwardly and their upper sides stepped outwardly, each of the blocks having a transverse partition and intermediate radial webs. 30
4. A conduit or the like made up of superposed courses of blocks, the blocks of the bottom course having their sides stepped inwardly or upwardly, the blocks of the top course having their sides stepped inwardly or downwardly, the blocks of the side courses having their sides stepped outwardly, the blocks of the courses between the bottom course and the side courses having their lower sides stepped outwardly and their upper sides stepped inwardly and the blocks between the side courses and the top courses having their lower sides stepped inwardly and their upper sides stepped outwardly, each of the blocks having a transverse partition and intermediate radial webs, the blocks of each course having lapping ends. 35
